UNITED STATES PATENT OFFICE

2,533,659

MARBLE SHOOTER

Joseph Yates, Bountiful, Utah

Application July 12, 1946, Serial No. 683,212

3 Claims. (Cl. 124—16)

1

My invention relates to toys and has for its object to provide a new and novel marble-shooting toy which may be utilized to shoot a marble in a marble game or on a playground or any other place desired in which the skill of direction rather than the skill of the fingers regulates the accuracy in shooting the marble.

A further object is to provide a simply constructed, highly efficient marble-shooting device having a pair of spaced apart gripping fingers between which the marble is placed and a trigger for release of the spring mechanism for shooting the marble from between the fingers.

These objects I accomplish with the device illustrated in the accompanying drawings in which similar numerals and letters of reference indicate like parts throughout the several views and described in the specification forming a part of this application and pointed out in the appended claims.

In the drawings

Figure 1 is a top plan view of the marble shooter with the spring released.

Figure 2 is a bottom plan view of the device.

Figure 3 is a vertical longitudinal section thereof.

Figure 4 is a front end or face view of the marble shooter taken from the end in which the marbles are placed ready for shooting.

Figure 5 is a view of the opposite or rear end of the marble shooter.

Figure 6 is a vertical longitudinal section of the device, parts being shown in elevation with the marble in place and the spring cocked ready for shooting the marble.

Figure 7 is a side elevation of Figure 1.

Figure 8 is a side elevation of the spring guide.

Figure 9 is an end view of Figure 8.

In the drawings I have shown my marble shooter as consisting of a cylindrical or tubular body 5 having one end open at 6 and provided with oppositely-disposed, laterally-offset, integral fingers 7 and 8 extending forwardly from the end of the body 5 and curved inwardly at 9 and 10 to grip the marble therebetween. The body 5 is made of a single sheet of metal formed into a tube with integrally-formed, downwardly projecting legs 11 and 12 on the forward end thereof. These legs are formed into an inverted Y-shaped supporting bracket by bending their lower ends outwardly at a and b. The intermediate portions of the legs are secured together by a clip or band 13, a supporting bracket at the forward end of the shooter being thus provided. The rear end of the body is provided

with lugs 13' adapted to be bent inwardly to hold a spring guide 14 in place in the body.

The spring guide 14 is a rod having a cylindrical head held in a sheet metal clamping strip 16 which forms a closure for the rear end of the tube 5. The strip 16 has a circular portion against which the head 15 is held by inwardly bent fingers as seen in Figs. 8 and 9. The strip and head are held in place over the rear end 10 of the tube 5 by bending the clips 13' thereover as shown in Fig. 5. A coil spring 17 within the tube surrounds a spring guide 14 and thrusts at its rear end against the closure 16, while the forward end of the spring enters the rear end 15 of a tubular marble projecting plunger sleeve 18. This shooting plunger 18 is also made of a single strip of metal bent to form a cylindrical tube of smaller diameter than the tube 5. The plunger sleeve telescopes into the tube 5 and has a loose sliding movement therein, being movable backward in the tube by a cocking finger 19. The latter is formed by bending two integral ears on the rear end of the sleeve 18 downwardly to extend through a longitudinal slot 20 in the bottom of the rear portion of the tube or cylinder 5, which slot is made between the two edges of the side walls of the plunger tube when it is formed.

One side of the bottom portion of tube 5 is provided with an integral ear which is bent back upon itself over the body of the tube 5 adjacent the forward end thereof to act as a stop 21 for the cocking finger 19 when the device has been shot or released.

A trigger projection 22 is formed on the rear end of the top side of sleeve 18 and is adapted to engage against an end wall 23 of a slot or opening 24 formed in the top of the rear end portion of the tube 5, when the device is cocked ready for firing, as shown in Figure 6.

Inwardly extended bosses 25 are provided adjacent the rear end of the plunger 18 to hold an abutment washer 26 in place therein, and against which washer the forward end of the spring thrusts. Thus, when cocking the shooter preparatory to shooting, the finger 19 is drawn back toward the rear end of the tube 5 and the spring is compressed around the spring guide 14, as shown in Figure 6. When the marble is in place between the spring fingers 7 and 8 and the device is cocked as shown in Figure 6, pressure on the top of the trigger 22 releases the plunger 18 causing its forward end to knock the ball from between the fingers 7 and 8 and shooting it forcibly therefrom.

It will be noted on reference to Fig. 6 that due to the looseness of the plunger sleeve 18 within the cylinder or body 5 and the provision of the upwardly projecting trigger projection 22 substantially diametrically opposite the cocking finger piece 19, that when the finger piece 9 is pulled rearwardly to compress the spring 17 there will be a tendency of the trigger projection 22 to move upwardly into the opening 24 and hook against the forward end wall 23 of that opening. By simply pressing the projection 22 downwardly out of the opening the opening the plunger will be released.

It will be seen that the entire device with the exception of the coil spring and its guide pin 15 may be inexpensively formed from a few pieces of sheet metal; and that the parts may be quickly and easily assembled to provide a strong, durable and effective marble shooter.

Having thus described my invention, I claim:

1. A marble shooting toy comprising a hollow cylindrical body formed from a single bent metal sheet and having in its top adjacent its rear end a trigger engaging opening, said body also having in its bottom at its rear end a longitudinal slot, the front end of said body being open and formed with a pair of integral, downwardly projecting clip-connected legs having outwardly bent ends to provide an inverted, Y-shaped support for the toy, a hollow cylindrical plunger loosely slidable in the open front end of said body and having at its rear end a cocking finger projecting downward through said slot, the rear end of said plunger having at its top a trigger projection to enter said opening in the body, a spring abutment in the rear portion of said plunger, a coil spring in the rear portion of said body and thrusting at one end against said abutment, and a closure for the rear end of said body and carrying a guide pin disposed within said spring.

2. A marble shooting toy comprising a hollow cylindrical body with open ends and formed in its top with an opening adjacent its rear end and in its bottom with a longitudinal slot extending forwardly from the rear end of said

body, means at the forward end of said body for releasably holding a marble, a cylindrical plunger loosely slidable in the front end of said body and having a depending cocking finger at its rear end slidable in said slot, the rear end of said plunger having on its top a trigger projection to engage in said opening in the body, a spring abutment at the rear of said plunger, a closure for the rear end of said body, and a coil spring in said body between said closure and said abutment.

3. A marble shooter of the class described comprising a single sheet of metal bent and formed into a cylinder with two strips of metal from the forward end extended down to form an inverted Y-shaped support for the forward end of the shooter and with a slot along the bottom side of said cylinder near the rear end; an inner plunger sleeve loosely slidable in said cylinder, said cylinder having a spring guide carried in the rear end thereof; a coil spring carried on said guide and within said cylinder to be compressed onto said guide when the shooter is cocked; a cocking finger extending downwardly from said sleeve and operable in said slot; and a trigger projection on the top of the sleeve to engage an opening in the top of the cylinder to hold the spring compressed, the spring being released by finger pressure on the top of said trigger projection.
